UNITED STATES PATENT OFFICE.

DANIEL CHISHOLM, OF UTICA, NEW YORK.

LAMP-HANGER.

SPECIFICATION forming part of Letters Patent No. 394,153, dated December 11, 1888.

Application filed January 26, 1888. Serial No. 261,944. (No model.)

To all whom it may concern:

Be it known that I, DANIEL CHISHOLM, of Utica, in the county of Oneida and State of New York, have invented certain new and 5 useful Improvements in Lamp-Hangers; and I do hereby declare that the following is a full, clear, and exact description of the invention, which will enable others skilled in the art to which it appertains to make and use the same, 10 reference being had to the accompanying drawings, and to the letters of reference marked thereon, which form part of this specification.

My invention relates to an improvement 15 in lamp-hangers, and more particularly to that class of hangers designed to be used with electric lights, although it is equally applicable to the use of any other system of lighting.

20 Figure 1 represents a side elevation of my improved lamp-hanger, the dotted lines indicating the position into which the same may be moved to enable the operator to adjust the lamp, the full lines representing its normal 25 position. Fig. 2 represents a top view of Fig. 1, the mast being shown in section. Fig. 3 represents a section of the outer end of the swinging arm and an end view of the head. Fig. 4 shows the bolt and connected parts for 30 straining the guy of the truss. Fig. 5 shows a frame used in the truss forming the arm. Fig. 6 shows a modified form of construction 35 of the outer end of the hanger-arm.

Similar figures of reference indicate like 40 parts in the several figures of the drawings.

In the drawings, 1 represents a mast or support usually employed in electric-light service. Although this is shown, it is quite obvious that my device can be applied to any 45 suitable means of support—such as the wall of a building or other similar structure which may be used as a support—and for convenience I term the same a "mast," on which hangers 2, Figs. 1 and 2, are supported. In 50 the hangers 2 I mount a vertically-swinging arm, 3, mounted in bearings 4 in hangers, in such manner as to allow the vertical movement of the arm in the arc of a semicircle. Pivotal bar 5 rests in the bearings with collars 6, which are longitudinally adjustable on the bar to allow the changing of the

arm or hangers, the collars being adjustable by the ordinary set-screw. In constructing arm 3 it is desirable to have a light arm so constructed as not to be swayed or moved by 55 the wind. To accomplish this I provide a frame, 7, forming a part of the arm and acting somewhat as a counter-weight to the free or outer end of the arm, and in the drawings the same is U-shaped, and is secured to pivotal bar 5 and the truss-work portion, consisting of head 8, to which are attached rods 9 9 9 9, Figs. 1 and 2, the rods passing through truss-frames 10 10, Figs. 1, 2, and 5, and connect with frame 7 and pivotal bar 5, respectively, as illustrated in the drawings. I provide guy or tightening rod 11, one end connected with head 8 and the opposite end with frame 7, so as to be tightened by nut 12, Fig. 4. Rods 9 9 9 are secured at their extremities by set-screws 13 13 13 13. I provide screw-eyes 14 14, which are inserted in cross-arm 15, passing through the head and formed of a material that is a non-conductor of electricity, thereby dispensing with the necessity of having the same insulated for attaching the lamp thereto.

For operating the swinging arm I preferably provide cable 16, Fig. 1, attached to the weighted end of the frame 7 and passing 80 through screw-eyes 17 17, Fig. 1, so as to be in reaching distance of the operator. By letting up on the cable the free end of the swinging arm, with the lamp thereto attached, drops down into the position shown in dotted lines 85 in Fig. 1, and may be moved backward into the position shown in full lines in the same figure, and, if desired, the free end of the arm may be moved into a vertical or any intermediate position, the same moving in the 90 arc of a semicircle—a point of great practical utility in furnishing a ready means of adjusting the height of the lamp.

What I claim as new, and desire to secure by Letters Patent, is—

1. A vertically-swinging hanger-arm having at its inner end a rigid weighted frame, a pivotal bar secured to the frame substantially at right angles to the plane of the frame, rods projecting from the frame and pivotal bar, a 100 head-piece upon the outer end of the projecting rod, the truss-frames, and straining-guy

- between the head and frame, in combination with hangers engaging the pivotal bar and securing it to a support outside of the arc of a circle described by the inner end of the arm.
- 5 2. The combination of a vertically-swinging arm for supporting an electric light, pivoted in hangers out of the vertical line of support, the inner weighted end passing between the vertical line of support and the pivotal point, the 25 head on the outer end of the arm, and the non-conducting cross-arm passing through the head on the outer end of the swinging arm provided with eye, substantially as set forth.
- 15 3. The combination, in a pivoted hanger-arm, of the rigid weighted frame, the pivotal bar secured to the frame, rods projecting from the frame and pivotal bar, the head-piece upon the outer end of the projecting rods, the 30 truss-frames, and the straining-guy between the head and the frame.
4. In a vertically-swinging electric-light-lamp hanger, the combination of the hangers affixed to a vertical support, the operating-cable, the eye upon the support, the arm having a rigid weighted U-shaped frame, a pivotal bar secured to the frame substantially at right angles to the plane of the frame, rods projecting from the frame and pivotal bar, the head-piece upon the outer ends of the projecting rods, the truss-frames, the straining-guy, the non-conducting cross-bar in the head, and the supporting-eyes, substantially as set forth, for the purposes stated. 35

In witness whereof I have affixed my signature in presence of two witnesses.

DANIEL CHISHOLM.
